(57) **CLAIM**

The ornamental design for a positioning arm for dental instrument, as shown and described.

DESCRIPTION

FIG. 1 is a perspective view of the positioning arm for dental instrument, showing the present design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view of thereof; and,

FIG. 7 is a bottom plan view of thereof.

The broken lines in the drawings depict portions of the positioning arm for dental instrument and form no part of the claimed design.
